UNITED STATES PATENT OFFICE

ADOLPH G. LOTTER, OF MILWAUKEE, WISCONSIN, ASSIGNOR TO H. C. MILLER COMPANY, OF MILWAUKEE, WISCONSIN, A CORPORATION OF WISCONSIN

LOOSE-LEAF BINDER

Application filed March 1, 1928. Serial No. 258,228.

This invention relates to certain new and useful improvements in loose leaf binders and refers more particularly to binders in which the leaves are held in position by arcuate ring members, the ring members being carried by two similar sections forming the back of the binder, which are hingedly connected and secured in their closed or locked position by spring catches.

10 Heretofore, the opening of a binder of this type was attended with considerable difficulty as two hands were required to release the spring catches positioned on each side of the binder and before the sections of the back 15 could be manually spread the catches would reengage themselves, and this invention has as a primary object the provision of means whereby the back member sections automatically spread upon the release of the spring 20 catches.

Another object of this invention resides in the provision of an improved loose leaf binder of the character described in which springs are mounted at the hinge connection between 25 the back sections which normally urge the sections to their open position whereby releasing of the spring catches automatically opens the sections.

And a further object of this invention resides in the provision of a loose leaf binder of the character described which is extremely simple in operation and constructed of a minimum number of parts.

With the above and other objects in view 35 which will appear as the description proceeds, my invention resides in the novel construction, combination and arrangement of parts substantially as hereinafter described and more particularly defined by the appended claim, it being understood that such changes in the precise embodiment of the hereindisclosed invention may be made as come within the scope of the claim.

40 In the accompanying drawing, I have illustrated one complete example of the physical embodiment of my invention constructed according to the best mode I have so far devised for the practical application of the 45 principles thereof, and in which:

Figure 1 is a perspective view of a loose leaf binder embodying my invention;

Figure 2 is a fragmentary, perspective view of the binder in its open position; and

Figure 3 is a transverse, sectional view, 55 taken through Figure 1 on the plane of the line 3—3.

Referring now more particularly to the accompanying drawing, in which like numerals designate like parts throughout the several views, 5 designates two complementary sections hingedly connected at their meeting edges, as at 6, to form the back of a binder; cover members 7 being hingedly connected to the sections 5, as at 8.

Each section 5 is preferably formed of bendable metal of substantially L shape in cross section having sides 9 and 10 forming the legs of the L and provided with end pieces 11 secured thereto in any desired manner. 70 The sides 9 of the sections have strips 12 secured thereto, adjacent their outer marginal edges to which arcuate shaped fingers 13 are riveted or otherwise secured. The fingers 13 of one section are staggered with respect to those of the other section to overlap each other when the sections are closed, as in Figure 1, and the leaves 14 are suitably apertured, as at 15, to receive the fingers 13.

The means for securing the sections in 80 closed or locked position comprises a hook shaped member 16 riveted or otherwise secured to the end member of one section and having a pair of locking lugs 17 with which a spring urged keeper 18 engages, the keeper 85 extending laterally from a member 19 pivotally connected with the end member 11 of the other section, as at 20. An operating button 21 secured thereto by a stud, which passes through an arcuate opening 22 in the end 90 member, provides means for actuating the keeper. A spring 23 coiled about the pivot 20 normally urges the keeper to its locking position, unlocking of the keeper being effected by moving the button 21 and consequently 95 the member 19 against the action of the spring 23. Both ends of the sections are provided with locking means as above described which are identical except that they are reversed, the hook member 16 of the opposite 100

end being carried by the section to which the keeper 18 is secured and vice versa.

In order to insure the opening of the sections as soon as the buttons 21 are actuated to release the locking means, springs 24 are coiled about the pivot 26 of the hinged connection 6 between the sections at spaced intervals. The springs 24 have their ends 25 engaged against the inner walls of the sides 10 of each section, to at all times urge the same to their open position, as will be readily apparent from Figures 2 and 3.

From the foregoing description, taken in connection with the accompanying drawing it will be readily apparent to those skilled in the art to which an invention of the character described appertains, that I have provided a loose leaf binder in which the sections of the back automatically open upon releasing of their holding means to thus obviate the necessity of manually spreading the sections.

What I claim as my invention is:

In a loose leaf binder, a pair of sections each having end pieces and a plurality of retaining fingers adapted to pass through apertures in leaves to be retained in said loose leaf binder, means hingedly connecting the sections for movement to and from closed position, a hook-shaped member carried by an end piece of one section, locking lugs extended from said hook shaped member, a pivoted keeper carried by the adjacent end piece of the other section to cooperate with one of the locking lugs to secure the sections in closed position, means for retracting the keeper, and means for moving the sections upon retraction of the keeper to engage the other hook-shaped member carried locking lug with the keeper to secure the sections in an intermediate position at which the ends of their retaining fingers overlap.

In testimony whereof I hereunto affix my signature.

ADOLPH G. LOTTER.
